UNITED STATES PATENT OFFICE.

IRVING L. DEMPSEY, OF GALENA, MARYLAND.

SASH-LOCK.

1,081,585.

Specification of Letters Patent. Patented Dec. 16, 1913.

Application filed March 7, 1913. Serial No. 752,800.

To all whom it may concern:

Be it known that I, IRVING L. DEMPSEY, citizen of the United States, residing at Galena, in the county of Kent and State of Maryland, have invented certain new and useful Improvements in Sash-Locks, of which the following is a specification.

My invention relates to window latches or locks, and particularly to that variety of latch which is used for holding a window sash at various elevations.

The object of my invention is to provide a latch or lock of extremely simple construction, neat in appearance and, when placed upon a sash, entirely out of the way, which lock will automatically hold the window at any height to which it is raised and which can be so set at any point in the movement of the sash that the window can neither be raised nor lowered, or which can be so set that the window will be automatically locked every time it is lowered so that it can not be raised from the outside, or so set that every time it is raised it can not be again lowered until the lock is properly adjusted.

Other objects and advantages will appear in the course of the following description.

My invention is illustrated in the accompanying drawings wherein:

Figure 1 is a perspective view of a portion of a window sash with my improved sash locking device in place thereon, the device being set to lock the window against movement either up or down. Fig. 2 is a sectional view of the side bar of the window sash and a portion of the window casing, showing the parts so set that the window will be locked from upward movement but will be free to be moved downward. Fig. 3 is a perspective view of a portion of the side rail of a window sash showing the lock casing and lock but with the front plate and actuating device removed. Fig. 4 is a perspective view of the front plate and the actuating device thereon.

Corresponding and like parts are referred to in the drawings by the same reference characters.

Referring to the figures, A indicates one of the side rails of a window sash and B the corresponding portion of a sash channel or window frame within which the sash moves. The sash is cut away on its outside face as at 2 to permit the positioning of my improved sash locking device. The case of the sash lock consists of a base plate 3 which

has outwardly extending flanges 4 at opposite ends, these flanges extending outward at right angles to the plate 3 and being then bent laterally as at 5 and provided with openings 6 for the insertion of screws holding the base of the casing in place. The walls of the recess 2 in the window sash are chamfered for the accommodation of the flanges 5. The other section of the case comprises a face plate 7 provided on one edge with an inwardly turned flange 8 which forms the front edge of the casing, this flange being cut away at the points 9 on each side of the middle to permit the projection 70 of the locking cams.

It will be noted that the edge of the plate 3 is cut away at 10 to receive the middle portion 11 of the flange 8 and that the plate 3 is also cut at its ends as at 12 to receive 75 the end portions 13 of this flange 8. The plate 7 is held to the base portion of the casing by means of screws 14 passing through openings 6 and 15 and into the wood of the window sash.

While I have illustrated what I deem to be the best form of casing, I do not wish to be limited thereto as it is obvious that it may be changed in many ways.

Projecting outward from the base plate 85 3 are the posts 16, and rotatably mounted upon these posts are the cams 17 and 18. Each cam is formed with a tail 19 which extends rearward and toward the central plane of the casing as illustrated in Fig. 2, and 90 surrounding each post is a coil spring 20, one end of which engages a projection on the outer face of the corresponding cam, the other end of the spring being extended rearward into the casing and bearing against 95 the end wall thereof. Preferably I form the cams with slots within which the tail members 19 are inserted, these tail members consisting of strips projecting outward from the face of the cam as illustrated in Fig. 3 100 and the hooked end of the spring 20 engages over this laterally projecting portion of the tail.

The face of the plate 7 is depressed as at 21, this depression being preferably, though 105 not necessarily, circular in form, and passing centrally through this depression is a post 22 carrying at its outer end a transversely extending handle or finger piece 23 which is housed within the depression 21. 110 The inner end of the post projects through the floor of the depressed portion 21 and at-

tached thereto is a three-armed actuating member designated 24 as illustrated in Fig. 4. These arms are arranged equidistantly and radiate from the axial center of the member 24. Two of these arms at their extremities are inwardly turned or bent as at 25 so as to engage the tails 19 of the cams. Stops 26 are preferably struck from the floor of the sunken portion 21 so as to limit 10 the rotation of this member 24. A stop 27 is struck up from the plate 3 at the middle thereof and in advance of a plane cutting the posts 16. The springs 20 act to urge the cams into such position that their tails 15 19 will engage this stop 27, the cams then being in the position shown in Fig. 3.

The operation of this invention is as follows. When the cams are in the position shown in Figs. 1 and 3, that is equally projected, the sash is locked and can neither be moved up nor down for the reason that if it is attempted to move the window down, the uppermost cam will wedge outward against the window and absolutely prevent 25 any downward movement thereof, while if the sash is attempted to be moved upward, the lowermost cam will operate in the same manner and wedge against the frame, thus holding the window stationary. In this 30 position of the parts, the lugs 25 engage in front of each of the tails 19 and the cams are free to turn without affecting the member 24. If now it is desired to permit the window to be shifted downward but to lock 35 the window from any upward movement, the parts are turned to the position shown in Fig. 2, that is, the handle 23 is rotated so as to carry the lug 25 of one of the radial arms into engagement with the tail of the 40 uppermost cam which will rotate this cam to the position shown in Fig. 2. This will shift the cam 17 out of operative engagement with the window casing but will leave the cam 18 free to act. As a consequence 45 the window may move downward but is locked from any upward movement for as soon as any upward movement occurs, the cam 18 will tend to rotate into even tighter wedging engagement with the window casing than if no attempt is made to raise the 50 window.

If it is desired to so arrange the parts that the window may be raised but can not be lowered, then the handle 26 is turned in 55 a direction reverse to that in Fig. 2 so that the tail 19 of the cam 18 is engaged by the turned down end 25 of one of the arms, thus rotating the cam 18 to an inoperative position but permitting the cam 17 to act.

60 With the parts in the position shown in Fig. 2 it is obvious that the window may be lowered and that when left in this lowered position it can not be raised, thus providing for automatically locking the window every 65 time it is lowered so that it can not be raised

from the outside, and automatically locking the window when it is raised so that it can not be lowered except by resetting the locking device. My improved lock thus permits in one position the window to be raised but 70 not lowered, in another position it permits the window to be lowered but not raised, and in a third position permits neither the raising nor the lowering of the window until the parts are properly set.

It will be noted from Fig. 2 that the stops 26 are so placed that the actuating member 24 can only turn through a limited distance and that the stops prevent either one of the arms carrying the lugs 25 from turning so far rearward that either lug will escape beyond the end of the tail 19 of the corresponding cam. Thus in Fig. 2 the lug 25 on the arm which actuates the cam 17 is disposed so that the extremity of the tail 19 80 engages against the middle of the lug 25 and the actuating device can not move any farther in the direction of the arrow in Fig. 2. The arm 19 is somewhat resilient to permit the lug 25 to ride over its end. 90 If the arm carrying lug 25 could move farther rearward than the position shown in Fig. 2, the tail 19 would escape beyond the inside face of the lug 25 and would prevent any return of the arm. Furthermore 95 if the lug 25 could not move so as to cause the tail 19 to bear against its face, the spring 20 would tend to return the parts to the position shown in Fig. 3 immediately that the handle or finger piece 23 was released. 100 By arranging the parts as illustrated, however, either cam will be locked in its retracted position when the actuating member is turned to fully withdraw either cam.

I do not wish to be limited to having the 105 tails 19 made separate from the cams 17 and 18 as they might be made integral therewith, but this is preferable for the reason that thereby I can secure the slight resiliency in the tail of the cam which is necessary for the most operative structure.

That portion of each peripheral cam face which is most nearly eccentric to the corresponding post 16 is smooth as at *a*, while that portion of the cam which is most eccentric to the post and which has binding or wedging engagement against the window casing is roughened or knurled as at *b*. Thus when the cams are turned to their inoperative positions, the face *a* will be opposed to the window frame and there will be very little frictional resistance. When, however, either of the cams is outwardly projected, its knurled face will be opposed to the sash channel and will cause it to have 120 frictional resistance with the face of the channel.

What I claim is:

1. A window sash lock including a casting, opposed cams eccentrically mounted, 130

- springs for urging said cams to a projected position beyond the edge of the lock casing, and a rotatable handle including an actuating device having outwardly divergent arms engageable respectively with said cams to rotate one of the cams to an inoperative position when the handle is turned in one direction and rotate the other of said cams to an inoperative position when the handle is turned in the other direction, and means on the actuating device for holding the cam with which the arm is engaged from accidental return movement. 2. A window sash lock including a casing, opposed cams eccentrically mounted therein, each having a rearwardly projecting tail, the tails normally extending toward each other, springs for urging said cams to a projected position beyond the edge of the casing, and an actuating member including outwardly diverging arms engageable with the tails of the said cams, said handle when rotated in one direction engaging the tail of one of the cams and rotating it to a retracted position and when rotated in the opposite direction engaging the tail of the other cam and rotating it to a retracted position, each of said arms having means thereon engageable with the tail of the cam to hold the cam in retracted position from accidental return movement. 3. A window sash lock including a casing, an eccentrically mounted cam disposed in the casing, a spring rotating the cam to a projected position beyond the edge of the casing, a tail projecting from the cam and having a laterally bent end, and a rotatable handle having a radially projecting arm formed with a lug at its extremity, said lug when the handle is rotated engaging with the tail to rotate the cam from a projected to a retracted position, the casing being formed with a stop limiting the rotation of the arm to a position where the extremity of the tail will engage with the face of the lug. 4. A window sash lock including a casing, opposed eccentrically mounted cams pivotally supported within the casing, that portion of the peripheral face of each cam which is most concentric to its axis of rotation being smooth, while that portion of each peripheral face which is eccentric to the center of rotation being roughened, a tail projecting rearward from each cam, said tails being extended rearward and curved toward each other and the middle plane of the casing, a stop formed upon the front of the casing with which said tails contact when the cams are projected, springs urging the cams to a projected position, and an actuating device including a handle, a rotatable post mounted within the casing, and radially projecting arms, each arm having a downwardly bent lug at its extremity normally extending in front of the corresponding tail, the face plate being provided with stops limiting the rotative movement of the handle to such position in either direction as will bring one of the lugs into engagement with the end of the corresponding tail. 5. A window sash lock including a casing, the face of the casing being formed with a depressed central portion, opposed cams eccentrically mounted within the casing and each having a rearwardly projecting tail, said tails extending toward the middle plane of the casing, a rotatable handle mounted within the depressed portion of the face of the casing and having a post entering the casing, radial arms mounted upon the post and extending over said tails and toward the front of the casing, each arm having a lug at its extremity disposed in front of a corresponding tail, springs urging the cams to a projected position, a stop limiting the forward movement of the tails, and stops limiting the rotative movement of the arms rearward in either direction to such position as will bring the lugs in contact with the ends of the tails.

In testimony whereof I affix my signature in presence of two witnesses.
